UNITED STATES PATENT OFFICE

OTTO WATZKA, OF VIENNA, AUSTRIA, ASSIGNOR TO CHARLES S. BLEICHER, OF NEW YORK, N. Y.

AUTOMATIC CONTRIVANCE FOR RECEIVING WRITTEN MESSAGES BY TELEPHONE

Application filed December 6, 1928, Serial No. 324,210, and in Austria April 21, 1928.

This invention relates to an apparatus for receiving in written form messages transmitted over telephone circuits; so that, when a party is called and is found to be absent, the caller is enabled, by manipulating the apparatus in a predetermined manner, to cause what he has to say to be written down at the other end of the circuit, for the party called to read upon his return.

10 An object of the invention is to provide an apparatus of such design that the message sent can be imprinted upon a strip of paper, by means of types which are brought successively into proper position to spell the 15 words of which the message is composed. The types are mounted upon a single movable member, which can be so actuated in accordance with impulses of electric current passing through the circuits, that the type presenting the desired letter, figure or other symbol can always be carried into operative position with respect to the paper, and an imprint of the letter or the like then produced.

In my copending application, Serial No. 25 320,026 filed the 17th day of November, 1928, for patent on automatic contrivance for receiving written messages by telephone, I have shown and described an arrangement of circuits together with certain parts for producing the same effects. This application covers particularly the essential mechanical construction of the parts of the contrivance by which the message is taken down, and the manner in which they are mounted so as 30 to be movable as required; and to that extent is supplemental to my copending application aforesaid.

In practice the apparatus is adapted to be utilized in connection with telephone circuits in which the connection with a called subscriber is given by means of a dial bearing letters and figures; so that the circuit of the subscriber to be called can be connected by working the dial to give the number and, if necessary, the local exchange as well. The apparatus, however, can also be used where the telephone equipment is not of the automatic type, but in such cases the caller's telephone must be furnished with a 45 dial if he desires to be able to send messages

and have them written down for the benefit of the party he is calling.

A further object of the invention is to provide a contrivance of this nature so designed that its principal parts are actuated and released by electromagnets through which impulses of electric current are passed; the apparatus including not only a member carrying the types and the necessary elements for causing the types to be brought into position, but also suitable parts for causing a strip or length of paper to be fed at the required speed past the member carrying the types, together with an inking element or typing ribbon which is likewise automatically moved in combination with the paper; and a type-bar or lever which strikes the paper and the typing ribbon against the types so as to cause the outline of the types to be imparted to and retained by the paper.

Another object of the invention is to provide an automatic contrivance for receiving written messages by telephone which is certain and effective in operation, made up of relatively few parts and very compact in its design and arrangement so that it can easily be installed in connection with any telephone apparatus now in use.

The nature of the invention and its further objects and advantages are set forth in the following description, taken with the accompanying drawings; by which a preferred form of the invention is illustrated. The disclosure, however, is explanatory only and details of shape, size and arrangement of various parts may be varied without exceeding the scope and meaning of the terms of the appended claims.

On the drawings,

Figure 1 is a front elevation of an automatic contrivance for receiving written messages by telephone according to my invention;

Figure 2 is a side elevation thereof;

Figure 3 is a top plan of certain of the parts for producing the feed of the inking ribbon and the paper upon which the message is recorded;

Figure 4 is a side view of said parts; and

Figure 5 shows a detail.

On the drawings the same numerals identify the same parts throughout.

In the particular description of the drawings, the numeral 1 indicates a drum or type-carrying member which is generally cylindrical in shape and bears a number of characters 2 in arc-shaped rows on its outer surface. With an axis of the member 1 vertical, as shown in Figure 2, the rows of type are horizontal and extend a given distance around the circumference of the member 1; and these characters may consist of letters, figures or other symbols. Member 1 is affixed to a spindle 3 and is held fast between collars 4 made fast on the spindle so that the member 1 is rigid with the spindle; but the spindle 3 and member 1 can rise and fall or be rotated together about the longitudinal axis of the spindle 3.

Thus to bring into position a particular one of the types to be printed on the paper, the spindle 3 and carrier 1 are first lifted to bring the horizontal row of types containing that particular character up to the required level; then the spindle and type-carrying member are turned to cause the particular type desired to be brought opposite the paper against which it is to be pressed. The invention contemplates the use of a so-called Strowger switch, well known in connection with automatic telephone circuits, to control the impulses of current which are sent through the circuits; and these impulses actuate a magnet to lift the member 1, a magnet to turn the member 1, and a third magnet to release the member and let it return to its original position. The Strowger switch, as set forth in my aforesaid copending application, is modified somewhat; having no contact track and no contact forks; and the recording of the message is effected entirely by the member 1 with the types 2 through actuation of this member in the desired manner.

The working parts of the contrivance are mounted upon a support comprising uprights 5, connected by a transverse bar 6, upon which is mounted a frame 7 between the uprights 5. At the outer end of the frame, spaced from the uprights 5, is a bracket 8 the lower end of this bracket being bent outward as shown at 9; and the lower half of the bracket being provided with a central vertical slot 10 which opens through the lower out-turned end 9 to make room for the spindle 3. To the lower face of the end 9 and bridging the slot 10 is affixed a member 11 having an opening to serve as a bearing in which the spindle 3 can turn and move up and down. The top of the bracket 8 is turned outward as shown at 12 and this top is centrally recessed to receive the spindle 3, but carries on its upper face a piece 13 bridging this recess, similar to the piece 11 and perforated to serve as another bearing for the

spindle 3. All the parts thus far described may be of metal.

The magnet for raising of the spindle 3 and the type-bearing member 1, is shown at 14; the magnet for turning these parts is 70 shown at 15 and the release magnet is shown at 16; all three of the magnets being mounted upon the frame 7. To carry these magnets I affix to the bracket 8 between the same and the uprights 5 a plate of metal 17 bent into the form of a U, the base of the U being directly secured to the rear of the bracket 8 and the arms of the U extending towards the standards 5. The magnet 14 is mounted by means of a part 18 secured to the upper arm of the U-shaped plate 17 by means of a screw or the like 19; this magnet, like the others, being an electromagnet with its axis in vertical position. Below it is the pivoted armature 20 supported above the lower horizontal arm of the plate 17. This armature projects forward and the spindle 3 carries a rack 21 made up of annular projections separated by grooves extending all around the spindle. This rack is normally disposed between the 90 bearings 11 and 13. To enable the armature 20 to lift the spindle 3 and member 1, it is provided at its outer end with a pivoted pawl 22, the upper end of which engages the rack 21 and the lower end of which is connected to 95 a spring 23 affixed to the armature 20. This pawl 22 may be mounted upon the armature 20 in any suitable manner and it will be located in the vertical slot 10 of the bracket 8. The lower arm and the vertical portion of the 100 bent plate 17 may be slotted as shown at 24 adjacent the slot 10, so that the armature 20 can move up and down; and the bracket 8 will have a projection 25 which extends into the path of the pawl 22 so that, as the armature lifts, the pawl will be deflected outward to engage the rack 21; and when the armature drops, it can slide along the teeth of the ratchet 21 without lowering the spindle 3. To this end the lower face of the circumferential teeth of the rack 21 are perpendicular to the axis of the spindle 3, while the opposite faces are inclined or rounded. A stop or projection 26 on the top of the bearing piece 11 in the slot 10 serves as a rest for 110 the armature 20 and pawl 22 in their lowermost position. The armature is provided at its end remote from the pawl 22 with down-turned ears 27 perforated to receive pivot screws 28 which engage projections 29 on the 115 horizontal part of the plate 17; and thus, while the armature is securely mounted, it can nevertheless move up and down about the pivot-screws as an axis. A spring is provided to act upon the armature 20 to resist the pull of the magnet 18; this spring being shown at 30. It has the form of a helical spring extending transversely of the frame 7 beneath the pivoted end of the magnet 20. One end of this spring is attached to the 120

125

130

135

projection 27a at the right in Figure 2; this projection extending downward past the pivot so that the spring 30 lies beneath the pivot but parallel with a line joining them. The 5 other end of the spring passes through an opening in the part 29 of the plate 17 and is there affixed to a flat head 31 which can be held in notches 32. By pulling this head out and turning it the torsion of the spring 30 is 10 varied. Normally the spring tends to hold the armature 20 down and pulls it down whenever the magnet 14 is dead.

The end of the upper arm of the U-shaped plate 17 is turned down as indicated at 33 15 and fastened to insulation 34 carrying several electrical contacts 35 which may engage contacts 36 of insulation at the top of the standard 5. These contacts enable connections to be conveniently made for energizing the magnet 14 and the magnets 15 and 16 as well.

As shown in Figure 1, the vertical rack bar 21 on the spindle 3 has a vertical slot therein indicated at 38; and attached to the 25 front of the bracket 8, a projection 39 has its extremity projecting into this slot. The slot affords clearance to the end of the projection 39, so that the spindle 3 may rise; but after the spindle is turned, the end of the 30 projection catches underneath one of the teeth of the rack 21 and then the spindle cannot move downward until it is turned back to bring the slot 38 and the projection 39 again into registry. I also mount upon the 35 apparatus for the rack 21 a movable catch 40, which is carried by the armature 60 of the release magnet 16.

The turning magnet 15 may comprise two 40 electromagnetic coils in horizontal or other convenient position. It is supported by a lateral projection of the U-shaped plate 17; this projection being located on the vertically-arranged part of the plate 17 and being bent towards the standards 5, so that the 45 screws 42 can engage one end of the frame of the magnet 15 and hold it in rigid position. Armature 43 of this magnet is arranged at the opposite end and it is movably secured in place by pivot-screws 44 in the 50 upper and lower arms of plate 17; this armature having a projection 45 to which is secured one end of a torsion spring 46, the other end of this spring being attached to the head 31a which fits into a counterbored recess in the upper end of the plate 17 having notches 55 so that the tension of the spring 46 can be adjusted in the same manner as already described in connection with the spring 30. This spring normally tends to make the armature 60 60 resist the pull of the magnet 15. The upper end of the armature has a lateral extension 47 which projects towards the spindle 3 and carries a pivoted pawl 48. This pawl is shown in top view in Figure 5 and has 65 the form of a bell-crank lever, one end of

which strikes a guide 49 on its working stroke and the other end of which strikes a stop 50 on the top of the upper end 12 of the bracket 8, on the return stroke of the pawl. The pawl 48 is maintained under tension by means of the spring 23a shown in Fig. 5. This pawl turns the spindle 3 by engaging the ratchet 51 which is made fast on this spindle above the bearing plate 13. Hence every time the armature 43 is attracted the ratchet 51 is 70 turned through the space of one tooth; which corresponds to the distance apart of the types of any one of the arc-shaped rows on the member 1. Further in the upper end 12 of the bracket 8 at the side opposite the block 50 is a stud 52 which passes through an opening in a plate 53, the opposite end of which is perforated to give passage to the upper end of the spindle 3. This plate 53 has a downturned projection 54 and the ratchet 80 wheel 51 has a stop 55, which strikes this projection 54 and thus limits the turning movement of the ratchet wheel 51, the spindle 3, and the type-bearing member 1. At 56 is a hollow cap receiving the upper end of the spindle 3 which projects through the plate 53 and this cap may be rigidly attached to the plate 53 so that it does not move; while the end of the spindle can turn in this cap 56. This cap may contain a spring made fast at one end to the inside of the cap and to the spindle 3 at the other; the spring in question being indicated at 57 in dotted lines. This spring is a torsion spring and normally tends to turn the spindle 3 and member 1 90 back to starting position but is overcome when the magnet 15 acts to turn the spindle 3 and drum 1.

The magnet 16 which is the magnet for releasing the spindle 3 and member 1 is 95 shown mounted on the top of the upper part of the plate 17, being fixed to a mounting piece 58 made fast to a projection 59 extending upward from one end of the upper part of the plate 17. To secure the magnet and projection 59 together I may use screws the same as the screws which secure the magnets 14 and 15. The armature for the magnet 16 is shown at 60 and it is pivoted by 100 means of screws 44a mounted in the upper and lower parts of the plate 17 the same as the screws 44 in the armature 43. The armature 60 is thus in vertical position turning about a vertical axis passing through the pivot screws 44. It carries a fixed projection 61 which acts as a stop for the ratchet 51 and carries at its lower end the fixed catch 40. To the armature is connected a spring 62; the other end of which is joined to a pin 63 held fast in a perforated projection 64 by means of a screw or other element so that the tension of the spring 62 can be 110 adjusted. The spring normally pulls the armature so as to turn it about its vertical axis and move the catches 40 and 61 into en- 115 120 125 130

gagement with the rack bar 22 and ratchet 51. When, however, the magnet 16 is engaged it pulls the armature 60 in the opposite direction, turning the armature about the pivot-screws 44a against the force of the spring 62 to withdraw the catches 40 and 61. As indicated in Figure 1, the magnet 16 is located to the rear of the pivoted middle of the armature 60, while the catches 40 and 61 are attached to a part of the armature which extends forward from the pivot-screws. Hence the pulling of the armature by the magnet withdraws the stops 40 and 61 and the interruption of the circuit through the magnet permits the spring 62 to pull the stops 40 and 61 into operative position.

Thus in practice when a message is to be written down impulses of current are first sent through the lifting magnet 14 which acts upon the armature 20 to lift the spindle 3 and type-bearing member 1 so as to bring into operative position the row of types which carry the letter or other symbol desired. The catch 40 engages the rack bar 22, spring 62 yielding, and permits the spindle 3 to rise step by step without allowing it to drop with the drum 1 downward. When the row of types containing the desired character has been lifted into position, the magnet 15 is energized by successive impulses to operate the armature 43 and through the pawl 48 to engage the ratchet 51 and turn the spindle 3 and the type-bearing member 1 until the required character comes opposite the paper. As soon as the turning of the spindle 3 begins, the fixed catch 39 no longer registers with the slot but projects between the adjacent teeth of the bar of the rack 21. The strip of paper is shown at 65 and the inking ribbon is indicated at 66. Both pass together over the type-carrying member 1 and between the same and a printing bar or lever 67 which is actuated by a magnet presently to be described to strike against the paper 65 and ink ribbon 66 and force them against the member 1. The ribbon 66 moves between the member 1 and paper 65 and when the printing lever 67 is thrown against the paper 65 it presses the paper and inking ribbon together against the type to be imprinted upon the paper. Then the release magnet 16 can be energized to attract the armature 60 to withdraw both catches 40 and 61. The spring 57 now turns the spindle 3 and member 1 until the vertical slot 38 in the rack 21 comes adjacent the fixed stop 39 and then the member 1 and spindle 3 can fall down to their former position.

The bar 67 is shown as mounted on a pivot 68 between two parallel supports 69 affixed to an upright 70. This upright also carries a magnet 71 below the parts 69, and when this magnet is energized it will attract the bar 67 with sufficient force to cause the upper end of it to strike against the paper 65 and typing

ribbon 66. The paper comes from a reel 72 mounted upon a pivot 73 carried by a support 74. The outer end of the frame 7 has downwardly-extending vertical bearings 75 at the two sides thereof beneath the end 9 of the bracket 8; and in these bearings are mounted round vertical bars 76 being secured in any suitable manner to the bearings 75 and end 9 of the bracket 8. These vertical bars 76 serve as supports for the members carrying the spools for the typing ribbon 66 which may be prepared like an ordinary type-writer ribbon. To one of these vertical bars 76 shown at the left in Figure 2, in affixed a lateral arm 77 by means of a clamp 78 and this arm 77 supports a bar or frame 79 having a guide 80 over which the paper 65 passes as it comes from the reel 72. This guide 80 may have the form of a suitable horizontal flanged roller mounted in bearings, with the paper 65 movable in contact with this roller and on to a second guide comprising a vertical flanged roller 81 in a suitable frame or bearing 82. From this flanged roller the paper strip 65 runs into a guide sleeve 83 and is drawn forward by the action of a magnet 84, which turns a feed roll 85 cooperating with another flanged guide roll 86, so arranged that the paper passes between the feed 85 and guide roll 86, as shown in Figure 2 at the right. This magnet 84 together with the rolls 85 and 86 are sustained from the other vertical bar 76 by means of a clamp 87 clamping this bar and made integral with an arm 88. To the arm 88 is attached a plate 89 which mounts the magnet 84; and this magnet has an armature 90, pivoted by means of screws 91 engaging the part 89; and having an extension 92 which projects from the pivot point where the screws 91 are located toward the other end of the magnet, and there carries lateral arm 93 to which is rigidly attached a pawl in the form of a flexible leaf-spring 94 having its end bent over to engage the teeth of a ratchet wheel 95; so that when the magnet 84 is actuated, the armature 90 is drawn toward the magnet 84 in such a way that the lateral arm 93 with pawl 94 move to the right in Figure 2. To support the ratchet 95 I affix a horizontal U-shaped frame 96 to the side of the frame or plate 89 supporting the magnet 84; and the ends of the arm of this frame 96 are perforated to receive the shaft or spindle 97 of the ratchet 95. Further attached to the bottom of the frame 96 is an arm 98 to which is pivoted the arm 99 which carries the guide roller 86. A spring 100 engages the outer end of the arm 98 and the outer end of the arm 99 in such a way as to force this arm with the roller 86 towards the roller 85, so as to keep the roller 86 pressing against the roller 85. Then as the magnet 84 acts it causes the bar 94 to turn the ratchet 95, so that the paper 65 is pushed forward between 130

the rollers 85 and 86 and thus drawn off the reel 72.

I may also mount on the top of the frame 96 a pawl 101 pivoted on a pin 102, which is 5 encircled by a spring 103. One end of this spring is rigid with the pawl 101 and the other rigid with the pin. This pawl 101 will act to hold the ratchet 95 and roller 85 every time they are turned one step by the armature 90 and prevent movement in the opposite direction.

The two spools of the typing ribbon 66 are shown at 104; the ribbon being unwound from the spool at the left and taken up upon 15 the other spool. The spool upon which the ribbon is unwound is supported upon a journal 105 capped by a retaining nut 106; this journal being affixed to one end of arm 77. The other spool upon which the ribbon is 20 taken up is mounted upon a journal 107, which carries a fixed ratchet wheel 108; to be engaged and turned by the armature of a magnet in the same manner as the ratchet 95 of the roller 85 is rotated. This magnet is 25 shown at 109 affixed to a support 110 in the form of a plate carried by the bar 88. The magnet 109 has an armature 111 pivotally mounted upon the plate 110 by means of screws 112. As shown in Figure 4, the plate 30 110 extends rearward of the adjacent vertical bar 76 towards the uprights 5; and the pivot screws 112 of the armature 111 are at the end of the magnet adjacent the standards 5. The armature has an extension 113, running forward beneath the magnet 109 and having on its end a lateral arm 93a with leaf-spring pawl 94a similar to the arm 93 and pawl 94 above described in connection with the armature 90. This extension 113 and pawl 94a 35 serve to engage the ratchet 108, so that every time the magnet 109 is energized the ratchet 108 is rotated through the space of one tooth. The plate 110 carrying the magnet 109 may 40 have affixed thereto a U-shaped horizontally-disposed frame 96a similar to the frame 96 above-mentioned, with the outer ends of its arms perforated for the spindle 107. The ratchet 108 will be below the frame of magnet 6 and the spool for taking up the type ribbon 50 above it. The lower arm of the frame 96a may also carry a pawl 101a to prevent backward movement of the ratchet 108.

Beneath the arm 77 is a support 115 carrying a number of leaf-spring contacts 116, and 55 the lower end of the lever 67 for striking the paper 65 may have an insulating knob 117 thereon to press upon these contacts and control certain circuits when the magnet 71 attracts this lever. The vertical bar 76 which 60 carries the clamp 78 has attached thereto another clamp 118 above the clamp 78, carrying plates of insulation and several spring contacts 119. These contacts may be controlled so that the end of one of them may be 65 bent to enter a vertical groove 120 in the mem-

ber 1; so that when this member turns into proper position the entrance into this groove of said contact will separate the two contacts at this point. Below the clamp 78 may be another clamp 121 carrying contacts 122 and 70 122a, which are separated when in lowermost position, by the weight of the drum pressing down upon a spring arm 123 which carries an insulating knob 124 to engage the lower contact 122a, which is longer, and move it out of engagement with the other contact 122. Similarly, the supporting plate 89 of the magnet 84 may have plates of insulation 125 secured thereto; and between their plates 75 spring contacts 126 which are movable by an insulating knob 127 on an arm 128 attached to the armature 90; and the supporting plate 110 for the magnet 109 may carry plates of insulation 129, separating spring contacts 130 which are controlled by a similar arm 128 with insulating knob 127.

These spring contacts may be connected with certain circuits which it is not necessary to describe herein, as the circuit connections and manner in which the electrical impulses are sent, are fully set forth in my copending application, above mentioned. It is sufficient to state here that as the spindle 3 is lifted and then turned to bring each type successively into proper position; then, as the magnet 71 is energized to cause the lever 67 to strike against the paper 65 and force it against the typing ribbon 66 and both the lever and the paper against the drum 1, to make the imprint of the letter, etc. the other 90 magnets 84 and 109 are actuated to cause the ratchet wheels 95 and 108 to pull the paper and the type ribbon step by step past the drum 1.

In operation, with the type-bearing drum 1 mounted both for upward movement and lateral movement, the person sending the message must dial so as to cause the spindle 2 and member 1 to be first lifted. He dials a certain number of times to lift the member 1 105 the required number of teeth with reference to the ratchet bar 21. This brings the row of letters on the member 1 containing the desired letter into position. The calling subscriber then dials again the required number 110 of times to turn the member 3 to carry the desired letter to a point opposite the paper and ribbon to imprint the letter upon the ribbon. Thus, for each letter or character on the drum 1, the calling subscriber must work the dial to get two different numbers; each pair of numbers bringing the desired letter into position; and then the magnet 71 is actuated to cause the bar 67 to make the letter imprint itself on the paper 65. After each letter is 115 imprinted, the release magnet 40 is actuated to withdraw the catches 40 and 61, whereupon the spindle 3 and member 1 return to the position they occupied at starting.

The member 1 can be provided with as 120 125 130

many arc-shaped rows of type, each row containing as many letters or other characters, as is convenient. For example, ten rows with ten letters would mean one hundred characters in all. At 131 are guide rollers for the ribbon 66, one on the frame 79 and the other on the guide 83. A collar 132 on the spindle 3 at the top of the rack 22, is engaged by the stop 39 to limit the downward movement of 10 the drum 1 and spindle 3.

I claim:—

1. A remote controlled printing apparatus comprising a type-carrying member with arc-shaped rows of type spaced axially apart on 15 its circumference, a spindle on which said member is mounted, a rack on the spindle consisting of annular teeth one face of which is abrupt and the other face bevelled, a longitudinal slot extending along said row of teeth, a stop having its end projecting into 20 said slot, and means for lifting and turning said member, the turning of said member causing the spindle to move the slot out of alignment with said stop to cause the stop to engage the rack and hold the spindle and member in lifted position.

2. In a remotely controlled printing apparatus, a type-carrying member, a spindle mounting said member, a frame having a 30 bracket with bearings at both ends to receive the spindle, a U-shaped plate attached to the bracket and having parallel portions extending laterally therefrom, magnets disposed between the parallel portions of said plate, 35 means actuated by the magnets to lift and turn the spindle, stops to hold said member in operative position and an additional electromagnet supported by said plate to withdraw the stops and permit return of the 40 spindle and member.

3. In a remote controlled printing apparatus, a type-carrying member, a spindle supporting said member, a frame having bearings receiving the spindle, a bracket carried 45 by the frame and mounting said bearings, the bracket being provided with a centrally located vertically extending slot, a rack on the spindle aligned with said slot, an electromagnet mounted on the rear face of the 50 bracket, an armature associated with the electromagnet and bearing a pawl projecting through said slot to engage the rack, and means for energizing the magnet for operating the armature to lift the spindle.

4. In a remote controlled printing apparatus, a type bearing member, a spindle to which the member is fixed, said spindle being mounted for axial reciprocation and rotation, a rack formed on said spindle longitudinally thereof, the teeth of said rack being each formed with a lower substantially horizontal face, a longitudinal groove intersecting the teeth of said rack, a stop member engaged in said groove, a ratchet wheel carried 60 by the spindle, means for engaging the rack 65

to raise the spindle and printing member step by step, means for actuating the ratchet wheel to rotate the spindle step by step, said stop member engaging under the horizontal face of a rack tooth when the spindle is rotated to maintain said spindle at a predetermined elevation during its rotational movement.

5. In a remote controlled printing apparatus, a vertically disposed spindle, a type 75 carrying member fixed to the spindle, means for raising the spindle step by step, means for maintaining the spindle at any elevation, means for rotating the spindle step by step, and means for locking the spindle against rotation until it has been raised from its initial position.

6. In a remote controlled printing apparatus, a substantially vertical support, a laterally projecting bracket carried thereby, a bearing support carried by said bracket in spaced relation to the support, said bearing support including vertically spaced bearings, a spindle mounted in said bearings for axial reciprocation and rotation, a U-shaped support secured to the bearing support and having its arms directed horizontally towards the vertical support, said bearing support being slotted in alignment with the spindle, and spindle actuating means mounted on said U-shaped support and including a lever operatively engaging the spindle through said slot and functioning to raise the spindle step by step, ratchet means carried by the spindle above the bearing support and means for rotating the spindle mounted on the upper arm of the U-shaped support, said means operatively engaging the ratchet wheel to rotate the spindle step by step.

7. In a remote controlled printing apparatus, a support, a bracket carried thereby, an axial reciprocable and rotary spindle mounted in the bracket, electromagnetic means for reciprocating and rotating said spindle carried by the support and cooperative interengaged switch parts carried by the support and bracket whereby said electromagnetic means may be electrically as well as mechanically connected to the support.

8. In a remote controlled printing apparatus, a support, a laterally projecting bracket carried by the support, vertically spaced bearing means carried by said bracket spaced from said support, a spindle mounted for axial reciprocation and rotation in said bearings and depending below said bracket, electromagnetic means carried by the bracket and disposed between the bracket and the support, pawl means associated with the magnets and engaging the spindle to rotate and axially shift the spindle when the magnets are energized, spaced vertical arms depending from said bracket on opposite sides of the spindle, a type carrying member carried by the spindle between said arms, an inking

ribbon operatively positioned with respect to the type carrying member, a ribbon spool mounted on each of said vertical arms, the ribbon passing from one spool to the other 5 transversely of said type carrying member, a paper supply associated with the type carrying member and means for printing a selected type on said paper.

9. In a remote controlled printing apparatus, a support, a bracket carried thereby, spaced bearing members carried by the bracket, a type bearing member, a spindle to which the member is fixed, said spindle being mounted for axial reciprocation and rotation in said bracket bearings, a rack formed on said spindle longitudinally thereof and disposed between said bearings, the teeth of said rack being each formed with a lower substantially horizontal face, a longitudinal 15 groove intersecting the teeth of said rack, a stop member carried by the bracket and engaged in said groove, a ratchet wheel carried by the spindle, means for engaging the rack to raise the spindle and type bearing member 20 25 step-by-step, means for actuating the ratchet wheel to rotate the spindle step-by-step, said stop member engaging under the horizontal face of a rack tooth when the spindle is rotated to maintain said spindle at a predetermined elevation during its rotational movement.

In testimony that I claim the foregoing as my invention, I have signed my name hereto.

OTTO WATZKA.
